UNITED STATES PATENT OFFICE.

SIDNEY C. GILBERT, OF NEWBERN, NORTH CAROLINA.

VENDING-MACHINE.

1,092,988.

Specification of Letters Patent. Patented Apr. 14, 1914.

Application filed April 8, 1913. Serial No. 759,623.

To all whom it may concern:

Be it known that I, SIDNEY C. GILBERT, a citizen of the United States, and a resident of Newbern, in the county of Craven and State of North Carolina, have invented a new and Improved Vending-Machine, of which the following is a full, clear, and exact description.

My invention relates to coin-controlled vending machines, and particularly to machines for vending peanuts in packages.

It is a design of my invention to provide an improved machine of the indicated character having a series of separate units, including carrying members and driven elements for actuating said members.

In carrying out my invention I prefer to make use of endless conveyers as the carriers, and sprocket wheels or equivalent actuating elements. A drive is provided, which desirably consists of a master wheel having a step-by-step movement controlled by an automatic stop and release, the functioning of the parts depending on the insertion of a coin, which in the illustrated example is made to close an electric circuit governing the stop and release of the drive. The drive is arranged to directly drive one of the units, and the units are provided with means whereby one unit, after it has discharged its merchandise, will actuate the next succeeding unit.

The distinguishing features of the invention, and the important structural elements characterizing the preferred embodiment which is illustrated as an example, will be more particularly explained in the specific description hereinafter to be given.

Reference is to be had to the accompanying drawings forming a part of this specification, in which similar characters of reference indicate corresponding parts in all the views.

Figure 1 is an external perspective view of a vending machine embodying my invention; Fig. 2 is a horizontal section; Fig. 3 is a partial vertical section; Fig. 4 is a fragmentary plan view on an enlarged scale, given to illustrate the means whereby one unit will actuate the succeeding unit; and Fig. 5 is a view similar to Fig. 4, showing the parts in position with the units in engagement with each other so that one will actuate the other.

In constructing a machine of the illus-

trated form, a suitable casing 10 is provided to contain the mechanism and the merchandise, said casing in practice, being of a size to accommodate any approved heating or roasting means, as is customary in machines of this general character. Within the housing is a frame supporting the movable parts, which frame may consist of side bars 11 and transverse end rods or shafts 12, 12^a, the said frame bars having suitable means, such as brackets 11^a, to sustain the frame within the casing.

Mounted on the shafts 12, 12^a, is a series of vending units, which may consist of endless chains 13 for carrying the merchandise, and sprockets for said chains, including drive sprockets 14 and idler sprockets 15, the chains being arranged in pairs having cleats 13^a to advance the merchandise as hereinafter explained. The hubs 14^a of adjacent drive sprockets 14 abut, as indicated in Figs. 4 and 5, the hubs being loose on the shafts 12. The upper runs or stretches of the conveyer chains 13 are run over a platform 16, which may have down-turned flanges 16^a secured to the sides of the casing 10.

The step-by-step drive desirably consists of a master wheel 17, the hub 17^a of which, at one side, is integral with the adjacent drive sprocket 14, and at the opposite side of the master wheel the hub is in the form of a drum 17^b on which winds a cord 18 which passes over an idler 18^a, and carries a weight 19, whereby to rotate the master wheel and drive the adjacent drive sprocket 14. The step-by-step movement is given to the master wheel 17, and this may be effected by producing notches 20 in said wheel to receive one arm 21 of a dog, the other arm 22 of which is under the influence of a retractile spring 23, normally tending to engage the arm 21 in a notch 20. The mentioned arm 22 constitutes an armature of a solenoid 24 arranged in an electric circuit 25 having one terminal contact 26 spaced from the coin chute 27 constituting the other terminal contact, the circuit being adapted to be closed by the passage of a coin 28 down the said chute and past the contact 26. The momentary closing of the circuit withdraws the arm 21 out of engagement with the notched master wheel 17, and permits the said wheel to rotate under the influence of the weight 19 until the next notch is reached, previous to which the circuit will be broken and the

armature 22 retracted by the spring 23 to engage the arm 21 in the next notch 20. The rotation of the wheel 17 will have actuated the adjacent driven sprocket 14 and advanced the chain sufficiently to have discharged a package A of peanuts or other merchandise. After the first unit has discharged its complement of packages it will engage and actuate the next succeeding unit 5 as follows: On the adjacent faces of the driven sprockets 14, oppositely-extending projections 29, 30, are provided, of a length to overlap each other, as shown in Figs. 4 and 5. In the completion of the movements 10 of the unit to discharge all its packages, the said projection will be moved from the position shown in Fig. 4 to that shown in Fig. 5, since the driven sprocket 14 is so proportioned to the conveyer chain, that one complete revolution of said sprocket will be 15 made during the total conveying movements of the chain. Thus the projection 29 will be brought to the back of the projection 30 and will have snapped beneath a resilient 20 catch 31, in the form of a curved arm on that driven sprocket 14 bearing the projection 30. Thus the end of the projection 29 will be securely held between the projection 30 and the co-acting catch 31. Upon the 25 next movement of the master wheel 17, the unit bearing the projection 29 will drive the adjacent unit bearing the projection 30, as will be obvious, and after the second unit 30 has discharged all its packages it will in turn actuate the next succeeding unit. 35

The capacity of the machine depends on the length of the individual units and on the number of the units. Between each of the 40 described units may advantageously be arranged vertical partitions 32 for guiding the packages and preventing them from becoming accidentally displaced. The packages are deposited in succession in the delivery trough 33, which opens at the front 45 of the machine. A door 34 affords access to the interior of the machine, additional doors being provided in practice, if desired, and similarly, the top 10^a of the casing may be removed when required.

50 Having thus described my invention, I claim as new, and desire to secure by Letters Patent:—

1. A vending machine, comprising a series 55 of units each having a driven element and a merchandise carrier actuated thereby, means on the units to actuate one by another after a predetermined movement of a unit, and a drive means for the units.

60 2. A vending machine, comprising a series 60 of units each having a driven element and a merchandise carrier actuated thereby, means on the units to engage and actuate one by another after a predetermined movement of a unit, and a step-by-step drive for 65 the units.

3. A vending machine having a series of units, and a drive therefor, said units having devices by which one unit will engage and actuate another after it has discharged its merchandise.

4. A vending machine having a series of units, a drive therefor, said units having devices by which one unit will engage and actuate another, and means for holding said engaging devices in engagement.

5. A vending machine comprising a drive, 75 a series of units each having a rotary driven element and a traveling merchandise-carrier actuated by said driven element, and devices on the said rotary driven elements 80 to establish actuating engagement of one unit with another after one has discharged its merchandise.

6. A vending machine, comprising a drive, 85 a series of units each having a rotary driven element and a traveling merchandise-carrier actuated by said driven elements, devices on the said rotary driven elements, 90 to establish actuating engagement one with another after one has discharged its merchandise, and a latch on each unit to hold the mentioned actuating devices of the rotary driven elements in engagement.

7. A vending machine, comprising a drive including a master wheel, a series of units 95 having sprocket chains and driven sprockets, oppositely-extending projections on the side faces of the driven sprockets of adjacent units adapted for engagement with each other, and means for giving the master wheel a step-by-step movement, said master wheel having driving connection with the sprocket wheel of an adjacent unit.

8. A vending machine comprising a plurality of carrying units, driving means 105 therefor, and means for establishing actuating engagement with the carrying units in succession, each of said units having initial travel to discharge its merchandise before actuating the next unit.

9. A vending machine, comprising a plurality of carrying units having members mounted to travel, a step-by-step advancing means for the units, and means for establishing actuating engagement with the carrying units in succession.

10. A vending machine, comprising a plurality of carrying units having members mounted to travel, and each unit being adapted to receive separately as series of 115 articles to be vended, a step-by-step advancing means to cause a unit to deliver merchandise, and means for establishing actuating engagement with another carrying unit upon one unit completing the discharge of its merchandise.

11. A vending machine, comprising a series of separate carrying units, each mounted to travel, driving means for actuating the first unit, and co-acting means on the units 120

adapted to engage each other to cause one to actuate another after a predetermined travel.

12. A vending machine, comprising a series of separate carrying units having members mounted to have longitudinal travel and revolving actuating devices, and co-acting means on the adjacent revolving devices to actuate one or another in succession.

10 13. A vending machine, comprising a series of separate carrying units each mounted to travel, and means on the units for actuating one unit by another in succession after the discharge of the goods by the unit, the

15 said carrying devices of the units consisting of sprocket chains, and the said driving means consisting of sprocket wheels, a driven master wheel having notches, a pivoted dog, a spring normally tending to en-

gage the dog with the notched master wheel, 20 and means for disengaging the dog.

14. A vending machine, comprising a series of traveling conveyers having driving means for said conveyers, a platform below the upper stretch of the conveyers, partitions rising from the platform and separating the conveyers from each other and forming guiding walls for the merchandise, and means for giving a step-by-step movement to the drive means of the conveyers. 25 30

In testimony whereof I have signed my name to this specification in the presence of two subscribing witnesses.
